UNITED STATES PATENT OFFICE.

RICHARD H. WILLET, OF WASHINGTON, DISTRICT OF COLUMBIA.

STAIR-CARPET FASTENER.

SPECIFICATION forming part of Letters Patent No. 349,329, dated September 21, 1886.

Application filed July 9, 1886. Serial No. 207,579. (No model.)

To all whom it may concern:

Be it known that I, RICHARD H. WILLET, a citizen of the United States of America, residing at Washington, in the District of Columbia, have invented certain new and useful Improvements in Stair-Carpet Fasteners, of which the following is a specification, reference being had therein to the accompanying drawings.

10 My invention relates to stair-carpet fasteners.

The object of my invention is the construction of devices which, when properly attached to the stairs, may be readily adjusted in position to securely hold in place the carpet, and in position to allow the carpet to be taken up without detaching the devices from the stairs, thus saving the time, trouble, and injury to the stairs attending the detachment of the devices now in use for this purpose.

In the accompanying drawings, Figure 1 is a perspective view of one of my improved devices detached. Fig. 2 is a perspective view of a portion of a carpeted stairway, showing my improved devices attached. Fig. 3 is a front elevation of a portion of a carpeted stairway, showing the positions of the devices adjusted to hold and to release the carpet. Figs. 4 and 5 are longitudinal sections, and Fig. 6 25 is a side elevation, of the devices, showing modifications of construction and attachment of the springs. Figs. 7 and 8 are plan views of the bearing-surfaces of the presser-plates, showing modifications in their construction. Fig. 9 shows the detached parts of one of my 30 devices.

A designates a bar, provided near its ends with the holes a' to receive loosely the fastening-screw and the shank of the presser-plate.

40 B designates a stud, provided with a base, b , and having a central hole to receive the fastening-screw c , which is extended through the bar and stud and screwed into the riser C of the stairs. The stud is made sufficiently long 45 to allow the required space for the movements of the presser-plate between the bar and the stair-riser, and the outer bearing-surface of the stud is trued so as to form a true bearing for the under side of the outer end of the bar (or the 50 spring when the spring is constructed to extend over the stud.) The bar A is thus pivotally attached to the stairs, so that it may be readily

adjusted in the different positions required, as hereinafter fully set forth.

D designates a presser-plate rigidly attached 55 to the inner end of the shank d , which is extended loosely through the hole a' in the pivoted bar. The outer end of the presser-plate shank is provided with a pull or knob, f , for operating the device, as herein described. 60

E designates a spring adapted to force the presser-plate against the carpet and hold it in place on the stairs.

It is evident that the invention does not depend upon any particular construction of the 65 presser-spring. It may be secured in place by being riveted to the bar, as shown in Fig. 5; or it may be constructed with the perforated portion h extended over the stud, as shown in Fig. 4 of the drawings; and instead of a flat 70 spring, as herein set forth, a coil-spring may be placed on the shank between the pivoted bar and the presser-plate, as shown in Fig. 6 of the drawings.

For the purpose of increasing the holding 75 capacity of the presser-plates, their bearing-surfaces are preferably corrugated, as shown in Fig. 8; or they may be provided with points b' , as shown in Fig. 7 of the drawings.

This device may be constructed of any suitable material and with any ornamental finish desired. It is very simple in construction, and not liable to get out of order or to be broken in use, and hence is durable and inexpensive, and, when once properly attached to 85 the stairs, need not be detached, except for purposes other than that of the removal of the carpet.

The devices are preferably attached to the lower portions of the risers of the stairs in 90 position for the presser-plates to extend slightly within the edges of the carpet and to press and hold the carpet closely and firmly against the risers and against the back portion of the steps, as shown in the drawings.

95 While I prefer to attach the devices to the risers, as described, they may be attached to the back portion of the steps, in which case the presser-plates will have their bearing upon the carpet over the back portion of the steps, close 100 to the lower portion of the risers.

The devices being properly attached to the stairs, as described and shown, and the carpet F being properly secured at its upper end and

drawn smoothly and tightly to its place over the steps, the presser-plates are drawn back so that they will swing clear of the carpet by pulling on the knob *f*, and the bar is turned down into position for the presser-plates to bear upon the edges of the carpet, as shown in the drawings. When the carpet is to be taken up, the pivoted bars are turned up, as shown in dotted lines, thus releasing the carpet without detaching the devices from the stairs.

What I claim as new, and desire to secure by Letters Patent, is—

1. A stair-carpet fastener consisting of a presser plate or foot having a yielding connection with an arm or a bar adjustably attached to a holder adapted to be fastened to a stairway beyond the lines of the edges of the carpet, whereby the presser plate or foot may be adjusted in

position to hold in place the carpet, and in position to release the carpet without detaching the device from the stairway, substantially as and for the purpose described.

2. In a stair-carpet fastener, the combination of the bar *A*, pivoted on the bearing-stud *B*, the presser-plate *C*, having the shank *d* extended through a hole in the bar, and provided with a pull, *f*, and a spring adapted to press the plate upon the carpet, substantially as and for the purposes described.

In testimony whereof I affix my signature in presence of two witnesses.

RICHARD H. WILLET.
